UNITED STATES PATENT OFFICE.

FRANK H. CLARK AND JOSEPH M. COFFEY, OF NEW YORK, N. Y., ASSIGNEES TO
CHAMBERS VALVE COMPANY, OF NEW YORK, N. Y.

THROTTLE-VALVE.

1,242,880.

Specification of Letters Patent.

Patented Oct. 9, 1917.

Application filed May 23, 1917. Serial No. 170,519.

To all whom it may concern:

Be it known that we, FRANK H. CLARK and JOSEPH M. COFFEY, citizens of the United States, residing at New York, in the county of New York and State of New York, have invented certain new and useful Improvements in Throttle-Valves, of which the following is a specification.

This invention relates to throttle valve actuating mechanism and more particularly to the actuating mechanism for the throttle valves of boilers of the locomotive type.

In order that a clearer perception of the present invention may be had it may be stated by way of explanation that the boilers of modern high power locomotives are rapidly approaching the limit of maximum diameter which results in the reduction in height of the superstructure such as the smoke stack, steam dome, etc. As is of course known in most cases, the throttle valve is located within the steam dome and it is necessary that the throttle valve be placed above the water line and as high as possible therein. The actuating mechanism therefore preferably extends outwardly through the side of the dome and thence rearwardly to the cab. For certain reasons throttle valves of the lift type are preferred, that is, valves in which the actuating mechanism is connected with the underside thereof and the present invention is directed more particularly to mechanism which permits the transmission of power from a point without the steam dome to this type of throttle valve.

With this explanation in mind some of the objects of the present invention are to provide a suitable throttle valve actuating mechanism for use in very low steam domes which will be of simple construction, inexpensive to manufacture and install, and reliable and efficient in use and operation. A further object is to provide a construction of the above general character in which a leakage of steam to the stuffing box is positively prevented when the throttle valve is closed. A further object is to provide a mechanism of the above character which permits inspection and repairing of the stuffing box, while the engine is under steam.

Other objects will be in part obvious from the annexed drawings and in part indicated

in connection therewith by the following analysis of this invention.

This invention accordingly consists in the features of construction, combination of parts and in the unique relations of the members and in the relative proportioning and disposition thereof, all as more completely outlined herein.

To enable others skilled in the art so fully to comprehend the underlying features thereof that they may embody the same by the numerous modifications in structure and relation contemplated by this invention, drawings depicting two preferred forms have been annexed as a part of this disclosure, and in such drawings, like characters of reference denote corresponding parts throughout all the views, in which—

Figure 1 is an elevational view partly in section showing such parts of the invention as are necessary to fully understand the same;

Fig. 2 is an elevational view partly in section taken at right angles to Fig. 1;

Fig. 3 is a detail, and

Figs. 4 and 5 show a modification.

Referring now to the drawing in detail 5 denotes a boiler shell provided with steam dome 6 within which is located a throttle valve box 7 having dry pipe connection 8 at the bottom thereof. The actual valve structure which forms no real part of the present invention is substantially the same as that illustrated and described in our prior Patent 1,220,729, March 27, 1917, except that the actuating connection is through the underside of the balance chamber instead of above the throttle valve as shown in this patent. It is believed that this requires no further detailed description.

On the outside of the steam dome 6 is located a stuffing box preferably of that character shown in our co-pending application Serial Number 98651, filed May 19, 1916, although other forms of stuffing boxes may be used if so desired. It is therefore believed to be sufficient for the present disclosure to permit the numeral 10 to represent the end of this stuffing box through which an actuating shaft 11 passes. This shaft is inclosed within a sleeve 12 passing through a flange or cover member 13 bolted to the throttle box 7 and provided with a

2

ground face insuring a substantially steam-tight construction. The actuating rod 11 is provided with a squared end fitting within a crank 14 whereby it may be easily moved out laterally as will hereinafter appear. The other end of the crank arm 14 is connected by means of a link 15 to the free end of a second crank 16 similar in size and shape to the crank arm 14. This crank arm 16 is mounted upon one end of a shaft 17, the opposite end of which is squared at 18 and is connected with the throttle valve crank arm 19 as shown. This construction insures equal or proportional angular movement of the two shafts 11 and 17.

The crank arms 14 and 16 together with the link 15 are mounted within a chamber 20 in the side wall of the throttle box and the shaft 17 passes through substantially a steam-tight connection in the partition to the interior of the throttle box which is just above the dry pipe connection. It will thus be seen that when the throttle valve is closed and there is no steam pressure within the dry pipe the actuating shaft 11 may be removed from the sleeve 12 to permit inspection or repacking of the stuffing box without danger of the steam escaping.

In Figs. 4 and 5, there is illustrated a slight modification showing a different manner of housing a portion of the power transmitting mechanism within the throttle box. In this construction, the vertical outer side wall of the chamber 20 is preferably made integral with the box. The shaft 11 passes through the sleeve 12 screwed into a boss on the side of the box where it connects with the linkage for transmitting movement to the shaft 17. This chamber or pocket 40 in the side of the throttle box is provided with a removable cover 21 secured to the box proper by means of bolts 22, or the like. A projection 23 within the chamber limits the movement of the upper crank arm and adjacent the shaft 17 in the lower part of the chamber is provided a removable plug 24 permitting access to the connection between the link or crank arm and shaft 17. The construction, method of use and operation 50 of this modification are substantially the same as above described in connection with the modification shown in Fig. 1.

It is believed that the construction, operation and method of use of devices of this character are clear from the above description and that a further discussion thereof is unnecessary. It will be seen that the invention is of simple and practical construction particularly adapted for use in connection with lift throttle valves on locomotive boilers having relatively low steam domes.

Without further analysis, the foregoing will so fully reveal the gist of this invention that others can by applying current knowledge readily adapt it for various applica-

tions without omitting certain features that, from the standpoint of the prior art, fairly constitute essential characteristics of the generic or specific aspects of this invention, and therefore such adaptations should and are intended to be comprehended within the meaning and range of equivalency of the following claims.

Having thus described our invention what we claim as new and desire to secure by Letters Patent is:

1. In combination with a steam dome having a throttle box therein, actuating mechanism therefor comprising a pair of shafts one of which extends through the steam dome for connection with the actuating mechanism within the cab and the other extends into the throttle box for connection with the throttle valve, and means connecting said shafts whereby they have equal angular rotation.

2. In combination with a steam dome having a throttle valve of the lift type, a pair of shafts one of which extends outwardly through the steam dome for connection with the actuating mechanism in the cab, and the other of which extends laterally into the throttle box for connection with the under side of the throttle valve, and means connecting said shafts including a parallel link connection for transmitting proportional angular rotative movement.

3. In combination with a steam dome having a throttle valve of the lift type, a pair of shafts one of which extends outwardly through the steam dome for connection with the actuating mechanism in the cab, and the other of which extends laterally into the throttle box for connection with the under side of the throttle valve, and means connecting said shafts for transmitting equal angular rotative movement, said connection comprising a crank arm on each shaft, and a link connecting said crank arms.

4. In combination with a steam dome having a throttle box therein containing a throttle valve of the lift type, a chamber in the side of said throttle box, a shaft extending from said chamber outwardly through the side of the steam dome, a second shaft extending from said chamber inwardly to the under side of the throttle, a pair of crank arms on said last mentioned shaft, a crank arm on the shaft extending outwardly through the steam dome, and a link connection between the latter crank arm and one of the crank arms on the shaft associated with the throttle box.

5. In combination with a steam dome having a throttle box therein containing a throttle valve of the lift type, a chamber in the side of said throttle box, a shaft extending from said chamber outwardly through the side of the steam dome, a sleeve extending from said chamber outwardly through the

dome and inclosing said shaft, a stuffing box associated with the sleeve at the point where it passes through said steam dome, a second shaft parallel with the first shaft extending 5 into the throttle box and connected with said first mentioned shaft for transmitting motion from a point without the steam dome to the throttle valve, said parts being so positioned and arranged as to permit a removal of the first mentioned shaft from 10 within its sleeve when the throttle valve is closed.

6. In combination with a steam dome having a throttle box therein, a valve of the lift 15 type within said throttle box, said box having a face containing a chamber, a removable steam tight cover for said chamber, a pair of parallelly disposed shafts one of which extends from the chamber outwardly 20 through the steam dome and the other from the chamber into the throttle box where it is connected with said throttle valve, and means connecting said shafts whereby they rotate proportionally.

25 7. In combination with a steam dome having a throttle box therein, a valve of the lift type within said throttle box, said box having a face containing a chamber, a removable steam tight cover for said chamber, a pair of parallelly disposed shafts one of which extends from the chamber outwardly through the steam dome and the other from the chamber into the throttle box where it is connected with said throttle valve, means 30 connecting said shafts whereby they rotate proportionally, said means including a crank arm on each shaft and a link connection therebetween.

8. In combination with a steam dome having a throttle box therein, a valve of the lift 40 type within said throttle box, said box having a face containing a chamber, a removable cover for said chamber, a pair of parallelly disposed shafts one of which extends from the chamber outwardly through the steam dome and the other from the chamber into the throttle box where it is connected with said throttle valve, means connecting 45 said shafts whereby they rotate proportionally, said means including a crank arm on each shaft and a link connection therebetween, each of said shafts having irregular 50 ends at their points of connection with the

crank arms whereby the parts may be easily disassembled by lateral movement on removal of the cover. 55

9. In combination with a steam dome containing a throttle box with a throttle valve therein, the wall of said throttle box containing a chamber having a removable cover, 60 a sleeve extending between the cover and the outer side of said steam dome having a stuffing box connection at its outer end, an actuating shaft removably mounted in said sleeve and extending from outside of the 65 dome into said chamber, a second shaft parallel with the first shaft extending from the chamber into the throttle box, and link connections between said shafts for producing proportional angular rotation thereof. 70

10. In combination with a steam dome containing a throttle box with a throttle valve therein, the wall of said throttle box containing a chamber having a removable cover, a sleeve extending between the cover 75 and the outer side of said steam dome having a stuffing box connection at its outer end, an actuating shaft removably mounted in said sleeve and extending from outside of the dome into said chamber, a second shaft 80 parallel with the first shaft extending from the chamber into the throttle box, link connections between said shafts for producing proportional angular rotation thereof, said means including a pair of cranks on each 85 shaft, one above the other within said chamber, and a link connecting the free ends of said cranks.

11. In combination with a steam dome having a throttle box therein, actuating 90 mechanism therefor comprising a pair of parallel shafts, said throttle box having a pocket in its wall with a removable cover at the top thereof, one of said shafts passing from the outside of the throttle box into the 95 pocket, while the other shaft extends from the pocket to a point below the throttle valve, and means connecting said shafts for producing proportional angular rotation.

In testimony whereof we affix our signatures in presence of two witnesses.
